UNITED STATES PATENT OFFICE.

CHARLES WILFRED BIRKIN, OF NOTTINGHAM, ENGLAND.

DESIGN FOR LEVERS LACE.

44,656.

Specification for Design. **Patented Sept. 16, 1913.**

Application filed July 29, 1913. Serial No. 781,875. Term of patent 3½ years.

To all whom it may concern:

Be it known that I, CHARLES WILFRED BIRKIN, a subject of the King of Great Britain and Ireland and the Isle of Man, and a resident of Nottingham, Nottinghamshire, England, have invented a certain new, original, and ornamental Design for Levers Lace, of which the following is a specification, reference being had to the accompanying drawing, forming part thereof, in which

the figure is a plan view of a portion of Levers lace, showing my new design.

I claim:

The ornamental design for Levers lace as shown.

CHARLES WILFRED BIRKIN.

Witnesses:

WILLIAM STOCKDALE,
MARJORY G. ROLLIN.
